US0D1032780S

(12) **United States Design Patent** (10) **Patent No.:** **US D1,032,780 S**
(45) **Date of Patent:** **** Jun. 25, 2024**

(54) **FILTER UNIT**

(71) Applicant: **Waterdrop Technology Co., Ltd.**,
Qingdao (CN)

(72) Inventor: **Zhibin Zou**, Qingdao (CN)

(73) Assignee: **Waterdrop Technology Co., Ltd.**,
Qingdao (CN)

(**) Term: **15 Years**

(21) Appl. No.: **29/842,048**

(22) Filed: **Jun. 10, 2022**

(30) **Foreign Application Priority Data**

Jan. 27, 2022 (CN) 202230058482.1

(51) **LOC (14) Cl.** **23-01**

(52) **U.S. Cl.**

USPC **D23/209**

(58) **Field of Classification Search**

USPC D23/207, 208, 209, 210, 355, 362, 363,
D23/365; D24/162

CPC B01D 27/00; B01D 2201/295; B01D
2201/305; B01D 2221/02

See application file for complete search history.

(57) **CLAIM**

The ornamental design for a filter unit, as shown and
described.

DESCRIPTION

FIG. 1 is a first perspective view of a filter unit showing my
new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG.
5; and,

FIG. 10 is an enlarged view of the selected portion 10 in
FIG. 6.

The broken lines shown in the drawings depict portions of
the filter unit that form no part of the claimed design.

1 Claim, 10 Drawing Sheets
